EUGENIO GALIZI AND ADRIANO GALIZI, OF NEW YORK, N. Y.

BASS STRAP FOR ACCORDIONS AND THE LIKE

Application filed October 1, 1928. Serial No. 309,389.

This invention relates to bass straps for accordions and musical instruments generally and has for its object to provide a connection for the ends of the strap within the 5 casing of the instrument.

One of the objects of our invention is to secure and clamp the ends of a strap within the body of the instrument including provision for preventing the ends of the strap 10 from tearing or becoming disconnected and further affording means for adjusting the length of the strap without detaching the same from the clamping means.

To enable others skilled in the art to more 15 fully comprehend the underlying features of our invention, reference is had to the accompanying drawing forming a part of this specification in which

Fig. 1 is a bottom plan showing the strap 20 in relation to the valve board cover.

Fig. 2 is a bottom plan showing the clamp and end of the strap when the valve board cover is removed.

Fig. 3 is a detail perspective of a preferred 25 form of clamp.

Referring now to the drawings wherein like reference characters designate corresponding parts throughout the several views, 30 5 designates in its entirety, the casing of an accordion or similar instrument, the keys being indicated by numeral 6, and the valve board cover by numeral 7. The bottom of the casing is provided with end notches 8, 9, in which the ends 10, 11 of the valve board 35 7 may be seated. Each end of the valve board 7 is provided with a recess for the passage of the end 12, 13, of a leather strap 14. The end 12 of the strap is attached to be secured within the body of the casing and 40 below the valve board cover 7, by a screw 13^a, having a thumb nut 14^a, bearing against a small plate 15.

Referring particularly to Figs. 1 and 2, 45 of the drawings, it will be noted that the opposite end 13 of the strap is recessed longitudinally as at 16, whereby it may straddle a threaded screw 17 passing through one end 18 of the casing. Within the body of the said casing, there is positioned a strap 50 clamp consisting of a plate 19, fastened by

screws 20 to the interior end wall 18 as clearly shown by Fig. 2. The plate 19 extends inwardly as at 20^a and the edge 21 is serrated throughout its length, the plate 19 being bent inwardly at the bottom 22 and is provided 55 or formed with bearings 23, 24 for a hinged pin 25 on which is mounted the complementary clamping plate 26. The upper end of the clamping plate 26 is also bent inwardly as at 27 and provided with a serrated edge 60 28. The head 29 of the screw 17 bears against the plate 26 so that when the knurled nut 30 is tightened on the outside end 18 of the casing, the split or recessed end of the strap 13 may be tightly clamped in position. It 65 will be understood that the serrated teeth of the clamping plates will bite into the end of the strap and thus prevents it from slipping. On the other hand, when the screw 17 is released, the end of the strap may be adjusted according to the length required by the player. When the valve board cover is once positioned, the clamping means for the ends of the strap is at all times concealed 70 and an adjustment may be made without removing the valve board cover. Furthermore, the end of the strap cannot tear or become disconnected since any relative movement of the strap is taken care of by the 75 slotted portion 16. 80

While we have shown and described our invention with some degree of particularity, it will be realized that other modifications and changes may be resorted to under special 85 conditions. We therefore do not wish to be limited and restricted to the exact details shown and described, but reserve the right to make such changes and modifications as may fairly fall within the scope of the subject matter now being claimed. 90

Having shown and described our invention, what we claim as new and desire to secure by Letters Patent is:—

1. In an attachment for an accordion case having a valve board cover, a bass strap, means for fastening one end of the strap in one end of the case and means for adjustably clamping the opposite end of the strap within and to the opposite end of the case. 95
2. In an attachment for an accordion 100

case having a valve board cover, a bass strap, means for fastening one end of the strap to one end of the case and a hinged clamp for fastening the opposite end of the strap to the inner end wall of the case.

5 3. In an attachment for an accordion case having a valve board cover, a bass strap, the ends of said strap passing through the cover to the interior of the case, means for fastening the end of the strap to one end of the case, the opposite end of strap having a slot, a hinged clamp and tightening screw attached to the opposite end of the case, said slotted end of the strap straddling the said tightening screw and adapted to be held in adjusted position thereby.

10 4. A bass strap clamp for accordions comprising a serrated plate, a serrated plate hinged to the first mentioned plate, a tightening screw for said plates, said screw being adapted to clamp the slotted end of a strap between said plates.

15 5. A bass strap clamp for accordions comprising a serrated plate, a serrated plate hingedly connected to the bottom of the first mentioned plate, the upper portions of said plates and serrations being disposed in parallelism to each other to receive the end of a strap therebetween, a tightening screw connecting said plates, said strap having a slot for straddling the tightening screw whereby said strap may be adjusted in clamped position between said plates.

20 In testimony whereof we affix our signatures.
